UNITED STATES PATENT OFFICE.

GRANT CAMPION AND MOTT WYANT, OF ANDERSON, INDIANA.

REGENERATOR-FURNACE.

SPECIFICATION forming part of Letters Patent No. 725,539, dated April 14, 1903.

Application filed June 2, 1902. Serial No. 109,969. (No model.)

To all whom it may concern:

Be it known that we, GRANT CAMPION and MOTT WYANT, citizens of the United States, and residents of Anderson, in the county of 5 Madison and State of Indiana, have made a certain new and useful Invention in Regenerator-Furnaces; and we declare the following to be a full, clear, and exact description of the same, such as will enable others skilled 10 in the art to which it appertains to make and use the invention, reference being had to the accompanying drawings, and to letters of reference marked thereon, which form a part of this specification.

15 Figure 1 is a section on the line 1 1, Fig. 3. Fig. 2 is a section on the line 2 2, Fig. 1. Fig. 3 is a section on the line A A, Fig. 2.

The invention has relation to improvements in regenerator-furnaces chiefly for the 20 manufacture of glass; and it consists in the novel construction and combinations of parts, as hereinafter set forth. In the ordinary construction of such a furnace no structural provision is made to keep the regenerator portion 25 free from slag, which flowing thereto clogs the regenerative chamber and stops the operation of the furnace until the slag is removed.

In the accompanying drawings, illustrating the invention, the letter A designates the regenerator-chambers of a glass-furnace, and 30 B the hearth, having the wall C, the top of which is above the level of the tops of said regenerator-chambers.

D represents the flue whereby the heat is 35 carried to the hearth, such flue extending through the lateral upper chambers E, built at the side of the regenerator-chambers, but communicating with such chambers at their upper portion, as indicated at a and b. The 40 lower portion of each lateral chamber is sunken below the flue-opening and forms a slag-pocket F. A series of these flue-chambers and slag-pockets are designed to extend along the side of the regenerator-chamber, 45 and underneath them is formed in the masonry a storage-chamber G, which commun-

cates with the lowermost portion of the bottom c of each slag-pocket by means of a tap-hole or passage H, through which the slag passes from the pocket into such storage-chamber, from which it is taken out from 50 time to time.

In the construction the top of the horizontal portion K of the flue D is sufficiently elevated to permit the heated gases from the 55 regenerator portion of the furnace to pass above the slag, which flows along its bottom from the hearth over into the vertical portion L of said flue and down the same into the slag-pocket F. In this way it is designed to 60 keep the regenerator-chamber of the furnace free from slag, and thereby in the operation of furnaces of this character to save the time which would be lost in cleaning them of the 65 slag.

Having described this invention, what we claim, and desire to secure by Letters Patent, is—

1. In a regenerator-furnace, the combination with the regenerator-chamber and the 70 hearth of the lateral flue-chamber, the slag-pocket in the bottom of such chamber, the flues connecting said flue-chamber and hearth, and the slag-storage chamber below and communicating with said slag-pocket, 75 substantially as specified.

2. In a regenerator-furnace, the regenerator-chamber, its lateral flue-chamber, the slag-pocket below the flue-entrance and flue-exit to such flue-chamber, the slag-storage chamber below said slag-pocket, and the passage or tap-hole from the bottom of the slag-pocket to said slag-storage chamber, substantially as 80 specified.

In testimony whereof we affix our signatures in presence of two witnesses.

GRANT CAMPION.
MOTT WYANT.

Witnesses:

KATE CHIPMAN,
DE WITT C. CHIPMAN.
